CLAIM

The ornamental design for a striped hose, as shown and described.

DESCRIPTION

FIG. 1 is an isometric view of a first embodiment of a striped hose;

FIG. 2 is a right side view thereof;

FIG. 3 is an enlarged detail view of portion "3" of FIG. 2, showing a braided surface texture that is illustrative of a surface texture of an entirety of the claimed portion;

FIG. 4 is a left side view thereof;

FIG. 5 is a front view thereof;

FIG. 6 is a rear view thereof;

FIG. 7 is a top view thereof; and

FIG. 8 is a bottom view thereof.

FIG. 9 is an isometric view of a second embodiment of a striped hose;

FIG. 10 is a right side view thereof;

FIG. 11 is an enlarged detail view of portion "11" of FIG. 10, showing a braided surface texture that is illustrative of a surface texture of an entirety of the claimed portion;

FIG. 12 is a left side view thereof;

FIG. 13 is a front view thereof;

FIG. 14 is a rear view thereof;

FIG. 15 is a top view thereof; and,

FIG. 16 is a bottom view thereof.

The broken lines shown in the drawings are for the purpose of illustrating environment that form no part of the claim. The dot dash broken lines indicate cutoff boundaries for enlarged detailed portion views and form no part of the claim. The stippling represents a contrast in appearance, not a surface texture of the claimed design.
